W. U. GRIFFITHS

WASH TRAY

Filed March 24, 1926

UNITED STATES PATENT OFFICE.

WILLIAM U. GRIFFITHS, OF PHILADELPHIA, PENNSYLVANIA.

WASH TRAY.

Application filed March 24, 1926. Serial No. 96,923.

My invention relates to improvements in wash trays; more commonly referred to, perhaps, as wash or laundry tubs.

More particularly the invention relates to improvements in the connecting and protecting means between the upper rear edges of wash trays and an adjoining wall, such trays being usually mounted or set up in adjacent relation to one of the walls of a room. The device of the invention is particularly well adapted for use in connection with wash trays made or constructed of sheet metal from which they may be formed by pressing or otherwise.

One object of the invention is to provide a wash tray having a novel construction of back wall strip provided with means whereby it is especially adapted for the connection of a hinge for the cover of a tray.

It is also an object of the invention to provide a connection between the rear upper edge of a wash tray and an adjoining wall of a room comprising a sheet metal strip of angular shape in cross section having means whereby its connection with the upper rear edge of the tray is facilitated; also having means whereby its connection with the adjoining wall of a room is facilitated; and also having means whereby hinged connection of the rear edge of the cover of the tray thereto is facilitated.

To these and other ends the invention comprehends the construction as hereinafter described in detail, particularly pointed out in the claims, and as illustrated in the accompanying drawing forming a part of this specification. However, it will be understood that the invention is susceptible of embodiment in other forms of construction than that shown and that changes in the details of construction may be made within the scope of the claims without departing from the principle of the invention.

In the drawing:

Fig. 1 is a vertical section through the upper portion of a wash tray, the cover therefor being shown in closed position, and a back wall strip embodying the invention also shown in section;

Fig. 2 is a top plan view thereof, a portion of the structure being broken away;

Fig. 3 is a fragmentary vertical section enlarged so as to bring out more clearly the features of construction; and

Figs. 4, 5 and 6 respectively are views in perspective of back wall strips of different lengths, the first being adapted for use in connection with a single tray, the second being adapted for use in connection with two wash trays located side by side, and the third being adapted for use in connection with three wash trays located side by side.

Referring to the drawing: 1 designates a wash tray of pressed metal the inside surface of which is adapted to be enameled with white enamel, while the opposite surface thereof may be provided with an enamel coating of speckled gray and white finish. The tray 1 is provided at its upper edge with a flange the inner portion 2 of which extends horizontally outward while the outer portion 3 thereof extends vertically downward. The back wall plate or strip for connecting the upper edge of the rear wall of a tray to an adjoining wall 4 of a room is formed of sheet metal the upper or outer surface of which may be covered with white enamel or enamel of any other preferred color. The said plate or strip comprises an intermediate substantially horizontal portion 6. The rear edge of the latter portion is provided with an upwardly extending flange 7 which is adapted to rest against and to be secured to a wall 4 by means of screws 8. At its forward edge the horizontal portion 6 is provided with a flange having a vertical downwardly extending portion 10 which terminates at its lower edge with a forwardly extending horizontal flange portion 11. The latter portion is adapted to rest upon, and in the completed structure does rest upon, the horizontal portion 2 of a flange at the upper edge of the rear wall of the tray 1. The portions 2 and 11 of the flanges upon the tub and upon the back wall strip or plate are secured together by means of bolts 15. The said bolts are held in position by means of nuts 16 upon the lower ends thereof. The vertical portion 10 of the flange at the front edge of the horizontal portion 6 of the back wall strip or plate affords a convenient means for the attachment of one wing 17 of a

95

100

hinge, the other wing 18 of which is secured to a downwardly extending flange 20 upon the rear edge of a sheet metal cover 21 for the tray 1. The cover 21 is provided with 5 a flange which extends entirely around its outer edge. The wings 17 and 18 of the hinges are connected to the flange portions 10 and 20 previously referred to by means of bolts and nuts 22. The rear edge portion 10 of the cover 21 is connected to the flange portion 10 in such manner that when the cover is in horizontal closed position its top surface occupies a position substantially in the same plane as that of the top surface of the 15 horizontal portion 6 of the back wall strip previously referred to. The cover is provided upon its opposite side edges with buffer blocks 23 of rubber or other suitable material. These blocks are secured to the 20 flanges of the cover upon the opposite ends thereof by means of nuts and bolts 24.

The back wall strips shown in Figs. 4, 5 and 6 are of the same construction as the back wall strips shown in Figs. 1, 2 and 3. 25 They are shown separately and in perspective in order that their exact construction may be more readily observed and also to indicate that the said strips may be of different lengths to adapt them for use in connection with one, two, three or more trays located in adjoining relation to each other. It will be noted that the strips shown in 30 Figs. 5 and 6 are provided with openings at intervals through the flange portions 10 for the purpose of permitting the connection of the cover hinges thereto, the said covers being adapted to cooperate with the respective wash trays associated with the respective back wall strips.

40 It will be seen that by my invention I am enabled to provide a construction of a character such that the fastening of the covers in place by means of hinges is facilitated; also that I have provided a construction by 45 means of which the usual unsightly wooden back strip is eliminated; also that I have provided a strip of a character such that water is prevented from being splashed over the rear wall of the tub into the space between the tub and the adjoining wall; and also a construction in which any water which 50 may be splashed up upon the back wall strip will find its way back into the tray and not onto the floor between the tray and the 55 wall near which it may be located.

Having thus described my invention, what I claim and desire to secure by Letters Patent is:

1. A wash tray of sheet metal, having a 60 horizontal flange at its upper edges, and a back wall strip of sheet metal having a rear flange adapted to be connected to a supporting wall and having an angular flange at its forward edge, said flange comprising vertical and horizontal portions the

latter portion resting upon the horizontal flange of the said tray, and means for securing the said horizontal flanges together.

2. A wash tray having a horizontal flange at the upper edge of its rear wall, a back wall strip of sheet metal having a vertical flange upon its rear edge which is adapted to be connected to a supporting wall and having an angular flange at its forward edge, said flange comprising vertical and horizontal portions the latter portion resting upon and being secured to the flange upon the upper edge of the rear wall of the wash tray, a cover for the tray, and means for pivotally connecting the rear edge of said cover to the vertical portion of the said angular flange. 75

3. A wash tray of sheet metal having a flange at the upper edges of its walls, said flange comprising horizontal and vertical downwardly extending portions, a back wall strip of sheet metal interposed between the upper edge of the rear wall of the said tray and an adjoining wall of a room, said strip being provided with an upwardly extending flange at its rear edge which is adapted to be connected to the said last mentioned wall and also having an angular flange at its forward edge, the said angular flange comprising a vertically downwardly extending portion and a horizontal forwardly extending portion, the latter portion resting upon the horizontal portion of the flange upon the said tray, means for securing the last two mentioned portions together, a cover having a downwardly extending flange upon its rear edge, said flange being adapted to occupy a position substantially parallel with the downwardly extending portions of the angular flange at the forward edge of the said strip, and hinges interposed between the flange upon the said cover and the vertical portion of the said angular flange the wings of which are connected to the said vertical flanges, substantially as described. 100

4. A wash tray of sheet metal, having a rearwardly extending flange at the upper edge of its rear wall, said flange comprising a horizontal portion, a back wall strip interposed between the upper edge of the said rear wall and the adjoining wall of a room in which the tray may be located, the said back wall strip comprising an intermediate horizontal portion, a vertical rear portion adapted to be fastened to the wall of the room and a front angular flange having vertical and horizontal portions, the latter portion resting upon the horizontal flange at the upper edge of the rear wall of the said tray, a cover for the tray the upper surface of which when in closed position is located substantially in the same plane as that of the upper surface of the horizontal portion of the said back wall strip, and the said covering having a downwardly extending 115 120 125 130

substantially vertical flange at its rear edge, a hinge located between the said last mentioned flange and the vertical portion of the said angular flange at the forward edge of the said back wall strip, one of the wings of said hinge being secured to the vertical portion of the said angular flange and the other

of said wings being secured to the flange upon the rear edge of the said cover, substantially as described.¹⁰

In testimony that I claim the foregoing as my invention I have hereunto signed my name this 4th day of March, A. D., 1926.

WILLIAM U. GRIFFITHS.
